UNITED STATES PATENT OFFICE

1,995,203

TENSION EQUALIZING DEVICE FOR SPINNING MACHINES

Harold W. Follmer, Selinsgrove, Pa.

Application August 16, 1933, Serial No. 685,451

2 Claims. (Cl. 117—23)

This invention relates to improvements in flyers as used in connection with spinning machines. Its object is to make more uniform and even the tension or pull on the threads, yarn, filament, 5 braid or strands in the process of spinning. The causes of such unevenness of tension or pull being made by various and varying speeds, weights and number of strands or units in the finished product, which may be called a thread, filament, 10 strand, yarn etc.

The device effects the balancing of the centrifugal force, caused by the weights of the thread, yarn, filament, strand or braid plus the speed of the spindle, plus the angulation of said 15 thread, yarn, filament, braid or strand through loops or eyes in a wire or silicon product plus the number of various and different strands or any combination of the above mentioned causes, by either a fixed, or a movable or adjustable counter- 20 balance on any flyer or mechanism used as such.

The various features of the invention will be more fully described in connection with the accompanying drawing in which:—

Figure 1 is a side elevation of one form of the 25 improvement in position on the spindle.

Figure 2 is a top plan view of the same.

Figure 3 is a side elevation of an equalizer mounted on a flyer above the flyer wires.

Figure 4 is a perspective view of the same.

Figure 5 is a sectional view of adjustable weight 30 used on equalizer arm showing spring fastening device.

Referring to Figure 1 of the drawing, 1 indicates a spindle of the usual tapered form, and 2 a bobbin mounted thereon. 3 indicates a wooden flyer block on the spindle 1 adjacent to the top of the bobbin 2 and prevented from changing its level by the mill nut 4, which may be held securely in any and all positions. 5 indicates the 35 wires of a four arm flyer secured to the flyer block 3 by any suitable means. The adjacent unthreaded arms of the flyer wires are held together by a counterbalancing weight 6.

Referring to Figure 3 of the drawing, 1 indicates the usual tapered spindle, 2 a bobbin mounted thereon and having a recess *a* in its top containing an inverted cup-like member *b* having an opening *c* therein arranged eccentric to the axis of the bobbin-spindle. An attaching 45 sleeve or barrel *d* is longitudinally split and is adapted to be fit over the spindle as shown in Figure 3. Fitting firmly and securely on the barrel *d* is a hub *e*, around the center of which are secured flyer arms *f*, and in an open-

ing or recess *g* is sprung a balance arm *h* which encircles the barrel *e* and may be movable or fixed on said hub *e*. On the balance arm *h* is a movable weight *j* adapted to be held in place by means of spring *k* the ends of which engage slots *l*. The invention is not limited in its application to the particular form of flyer herein described, but may be used on any form of flyer.

The operation of the device is as follows:—
In the spinning of thread, yarn etc., the material is taken from a bobbin or spool that is fastened to a rapidly revolving spindle, and the materials to be spun are passed through eyes of a flyer and thence to a slowly revolving take-up 10 bobbin or spool. In its passage from the bobbin on the spindle to the take-up bobbin the material is twisted upon itself in the direction desired, either clock-wise or counterclock-wise. The material to be twisted of varying diameters and 15 weights, plus the R. P. M. of the spindle produce a centrifugal force which causes a variation of the tension of the material twisted. The angulation between the eyes of the flyer also causes a variation in the tension of the twisted material. 20 This variation of tension on the materials as they are being twisted causes variable degrees of thickness in the diameter of the finished twisted product. The difference of the thickness of the 25 twisted product causes defective woven cloth. 30 The object of this invention is to counterbalance the contributory elements that cause the uneven tension by having on the flyer or flyer wires a counterweight that will keep the angulation between the threaded flyer wires constant and keep 35 the flyer in a right angle position to the spindle.

What I claim and desire to secure by Letters Patent is:—

1. A flyer for spinning machines and the like, comprising a member adapted for attachment to 40 a bobbin spindle above the bobbin, flyer wires disposed on said member, an arm disposed on said member above the flyer wires having a movable counterbalancing weight, means for securing said weight in predetermined positions on said 45 arm, for the purpose specified.

2. A flyer for spinning machines and the like comprising flyer wires disposed on a bobbin spindle, an arm encircling said spindle above said flyer wires, a movable weight disposed on said arm, 50 means for securing said weight in predetermined positions on said arm, for the purpose specified.

HAROLD W. FOLLMER.
